UNITED STATES PATENT OFFICE

2,008,624

CLASP

Edwin S. Mix, Rochester, N. Y., assignor to
Hickok Manufacturing Company, Inc., Rochester, N. Y., a corporation of New York

Application December 20, 1934, Serial No. 758,484

16 Claims. (Cl. 24—49)

This invention relates to clasps.

In the use of clasps, particularly garment clasps, of that type employed for necktie holding purposes, it is essential that the clasps and parts 5 associated therewith be of an ornamental nature and they are generally composed of gold, silver and other precious metals. These precious metals are more or less expensive, increasing the cost of production of the articles. There are times 10 when such articles are nickel plated or otherwise enameled and the polished surfaces of the articles become discolored and worn.

It is therefore one object of the present invention to provide a clasp for garment holding or 15 other purposes and obviate the expensiveness of gold, silver and other precious metals as well as the unsatisfactory enameled finishes to common metals and provide a new and highly ornamental article of adornment by the use of common inexpensive metals covered with non-metallic materials of a character to appeal to the aesthetic 20 senses of those interested in or looking upon articles of the present character.

Another object of the present invention resides 25 in the provision of a necktie holder ornamented and embellished by means never before contemplated in the necktie holding art, in particular, as far as I am aware, and which is accomplished by means not only such as to appeal to the aesthetic 30 senses, but at the same time provide for an increase in frictional engagement of the clasp with the necktie or other wearing apparel to which it may be applied as well as to prevent injury or 35 pressure marks being formed or impressed on neckties or other wearing apparel by the clasp. In other words, in one instance of embodiment 40 of the present invention, a clasp constitutes the necktie holder and it includes an ornamental bar adapted for disposition across the front of the necktie. The back of the bar, through the 45 instrumentality of my ornamenting and embellishing means, is caused to present a surface of material on the rear face or back of the front bar to contact with the front face of finely woven or other fabric neckties to prevent injury to the 50 front of the necktie or the formation of pressure marks on the front and rear faces of the necktie.

A still further object of the invention is to provide something new in the way of an article of 55 adornment particularly designed in structure in the nature of a clasp for wearing apparel of a character capable of embellishments not permissible with clasps composed solely of exposed metal or similar material.

It is still further designed to provide a new

article of manufacture in which the coldness and hardness of metal is enveloped or in part at least covered by a softer material resulting in the production of an article of manufacture pleasing to the eye and resulting in the production of certain articles giving an entirely new effect and a different appearing article than heretofore known in certain arts.

With these and other objects in view, the invention consists in the construction and novel 10 combination and arrangement of parts herein-after fully described, illustrated in the accompanying drawings and pointed out in the claims hereto appended, it being understood that various changes in the form, proportion and minor 15 details of construction, within the scope of the claims, may be resorted to without departing from the spirit or sacrificing any of the advantages of the invention.

In the drawings:—

Fig. 1 is a front elevation of the invention applied to a shirt and necktie.

Fig. 2 is a horizontal longitudinal sectional view on the line 2—2 of Fig. 1.

Fig. 3 is an elevation of the clasp when not in 25 use.

Fig. 4 is a transverse sectional view through the front bar of the clasp showing a modification.

Fig. 5 is a transverse sectional view through the front bar illustrating a modification of the 30 invention.

Fig. 6 is a similar view showing another modification of the invention.

Fig. 7 is a front view of the front member of 35 the clasp showing a modification of the invention.

Fig. 8 is a transverse sectional view on the line 8—8 of Fig. 7.

Fig. 9 is a face view of the front bar showing 40 still another modification of the invention.

Fig. 10 is a transverse sectional view on the line 10—10 of Fig. 9.

Fig. 11 is a face view of still another modification of the invention.

Referring now more particularly to the accompanying drawings, the reference character A indicates one type of clasp which may be used for necktie holding purposes but equally as well usable for other purposes. The particular type of clasp illustrated forms no part of the present invention and is shown merely for purposes of illustrating the present invention. The specific form of clasp illustrated is fashioned after the clasp illustrated in my Patent No. 1,981,740 dated November 20, 1934, and therefore, the particular 45

clasp need not be described in detail herein. Suf-
fice it to relate that the clasp illustrated includes
a front bar 1 of any suitable inexpensive or other
metal having one end bent, as at 2, and bifur-
cated as at 3, to form a support for a spring
pressed lever 4 having toothed or other segmental
shaped side flanges 5 adapted to coact with the
rear face or back of the front bar 1 for clasping
purposes.

10 The clasp is adapted to connect the necktie 6
with the buttonhole hem 7 of the wearer's shirt
8, with the ornamental front bar 1 lying sub-
stantially transversely across the front of the
necktie. Obviously, the two flaps of the necktie
15 may be connected together by the clasp without
connecting the clasp with the wearer's shirt and
it is equally obvious that the inner flap and shirt
may be connected together by the clasp if de-
sired and particularly when it is preferred not
20 to display the ornamental front bar across the
front of the necktie.

It is the front bar of the clasp which is gen-
erally exposed to view in the use of the present
article as a necktie holder, and it is therefore this
25 front bar which it is my purpose to give a new
and highly ornamental effect. To this end, I may,
in some instances, completely envelop the front
bar 1 by a covering of plain or ornamental mate-
rial forming a sheath for the front bar and com-
30 posed of various leathers, such as snakeskin, calf-
skin, pinseal, lizard, alligator or the like, or the
covering may be of plain or variegated fabric ma-
terial. In other instances, the front bar 1 may
be but partially covered by such or similar ma-
35 terial.

As shown in Figs. 1 to 3, inclusive, the bar 1 is
preferably covered by suitable covering material
9 of any suitable ornamental nature and which
40 preferably extends from the free end of the bar
1 to the inner end thereof and preferably over a
portion of the bend 2 of the clasp, as shown. In
some instances, the covering 9 may be made up in
tubular form in any suitable manner open at one
45 end and slipped or telescoped over the front bar
1 after the front bar 1 has been primed with a
coat of cement or any suitable adhesive. If pre-
ferred, the interior of the tubular covering 9 may
be primed with a cement or adhesive or both the
50 interior of the tube and the bar may have a ce-
ment or adhesive applied thereto prior to the ap-
plication of the tube 9 to the bar 1. When the bar
1 and the covering 9 are thus placed together
they are effectively connected together under the
55 influence of the cement or adhesive material by a
pressing of the two together.

By virtue of the softer material, such as leather,
fabric or the like applied to the hard metallic
front bar, and especially to the back of the latter
the finely woven fabric or other neckties will not
60 become injured or have formed thereon pressure
markings incident to the clasping of the neckties,
and if desired the back of the bar could be padded
or otherwise soft material used on the back of the
bar and enveloped by the covering 9 as indicated at
65 10 in Fig. 4. This padding material 10 would co-
operate with the clasping end of the lever 4, but
whether the padding material 10 is employed at
the back of the front bar 1 there results consider-
ably greater friction in contact with the necktie
70 than where metal to metal clasps the necktie to
the wearer's shirt. With or without the padding 10
there is a cushioning effect of the pressure of the
lever 4 against the bar with the shirt and necktie
or either between the clasping member and the
75 front bar 1. Padding material other than the

strip of padding material 10 shown could be em-
ployed.

The back surface of the front bar may be em-
bossed with some satisfactory pattern such as
"knurled" or "fluted" characteristics to more se-
curely effect closer adhesive connection between
the bar and the covering. The covering mate-
rial of whatever material employed prevents slipping
of the clasp on the tie and prevents imparting
10 and injurious pressure which would otherwise
mark the necktie as previously stated. If desired
the back of the covering material itself may be
"knurled" or "fluted" or otherwise roughened to
further aid in preventing slipping of the clasp on
the necktie.

15 The covering for the bar 1 need not necessarily
be composed of a tubular member as described.
The covering may be composed of a sheet 11 which
may be wrapped around the bar 1 and a portion
of the bend 2 and the horizontal edges of the sheet
20 disposed in abutting relation as shown at 12 in
Fig. 5 or the longitudinal edges of the sheet may
be overlapped as shown at 12a in Fig. 6. In either
of these last forms both the bar and the inner
face of the covering material or either may have
25 cement or a suitable adhesive applied thereto
prior to applying the covering to the bar by pres-
sure or otherwise and of course the covering may
be otherwise applied to the bar if desired so long
as an effective connection between the bar and
30 covering is made to prevent slipping relative to
each other.

35 As shown in Figs. 7 and 8 any one of the afore-
said or other coverings may be cut away at the
front and upper and lower edges of the bar mid-
way between the ends of the bar to expose the
front bar at such portions. Such exposed portion
may be given a paneled effect as indicated at 13
either before the covering is applied or after the
covering has been applied and a portion cut away
40 as stated. Instead of the panel 13 it is obvious
that an initial, emblem or other symbol may be
formed on the exposed portion of the bar.

Instead of cutting away the front portion of
the covering the latter may remain complete and
45 a panel or decorated band 14 of any suitable mate-
rial may be securely fastened in any suitable
manner around the covered bar as shown in
Figs. 9 and 10 or as shown in Fig. 11 a helical
strip 15 may be secured in any suitable manner
50 around a central portion of the covered bar.
Various other methods of decorating the orna-
mental bar may be employed in carrying out the
objects of the present invention.

It will thus be seen that by virtue of the pres-
55 ent invention I am enabled to provide clasps for
necktie holding or other purposes having various
coloring characteristics to effectively blend with
differently colored neckties or other articles of
wearing apparel worn by the wearer and that in
60 addition to a highly ornamental new type of clasp
it embodies functional characteristics essential to
articles of the present character in order to pre-
vent dislocation with relation to wearing apparel
as well as to overcome possible accidental loss
65 of the article.

What is claimed is:—

1. A garment clasp including a bar adapted
in use to extend over the front of the garment,
a clasping member carried by the bar and coact-
70 ing with a portion of the rear surface of the bar
for clasping purposes, and an ornamental cover-
ing for the bar having at least a portion thereof
over the rear surface of the bar forming a non-
slipping surface at the rear face of the said bar
75

- to coat with the clasping member and of a material to increase friction between the bar and the garment over which the covering extends.
2. A necktie clasp having a bar adapted in use to extend over the front of a necktie, a member carried by and coacting with the bar to clasp a shirt front and the necktie between said member and the rear face of the bar, and an ornamental covering for said bar having a part thereof extending across the rear surface of the bar and increasing the frictional contact of the bar with the engaged portion of the necktie and forming a non-slipping tie engaging surface to coat with the said member in clasping the necktie.
3. A necktie clasp having a bar adapted in use to extend over the front of a necktie, a lever carried by and coacting with said bar to clasp the tie and portion of a shirt front between them, and an ornamental covering for the bar adhesively united thereto and extending across both the front and rear faces thereof, the covering at the rear face of the bar forming a non-slipping tie engaging surface to cooperate with the lever in clasping a necktie.
4. A necktie clasp including a bar adapted in use to extend over the front surface of a necktie and a member carried by and coacting with said bar to clasp the tie and a portion of a shirt front between them, and an ornamental fibrous covering for the bar adhesively united thereto and concealing the same and forming a non-slipping tie engaging surface at the rear face of the said bar to cooperate with the said member.
5. A new article of manufacture including a bar of substantially uniform cross-sectional area and an ornamental tubular covering open at one end and telescopingly fitted on and permanently secured to said bar.
6. A new article of manufacture including a front member of substantially uniform cross-sectional area and a clasping member coacting therewith, and a tubular ornamental covering open at one end and closed at the other end and telescopingly fitted on and permanently secured to said front member to conceal the latter and forming a non-slipping tie engaging surface at the rear face of the front member to cooperate with the clasping member.
7. A new article of manufacture including a front metal member and a rear metal member coacting therewith to clasp a necktie, and a covering for the front member of softer material than the front member and forming a non-slipping tie engaging surface at the rear face thereof to cushion the clasping action of the rear member.
8. A clasp comprising a front member and a rear member coacting with the front member for clasping purposes, a covering for the front member, and a padding material between the rear face of the front member and the covering.
9. A clasp including a front rigid metal member, and an ornamental fibrous covering enveloping the front member and secured thereto and forming a non-slipping gripping surface at the rear face of the front member.
10. A clasp including a front metal member and a flexible fibrous covering on the front member and fixedly secured thereto throughout its length and when secured thereto assuming the appearance of the rigidity of the front metal member but softening the exterior surface thereof and thereby in use increasing the frictional resistance of the front member with relation to materials clasped thereby and at the same time forming a non-slipping gripping surface at the rear face of the front member.
11. A necktie clasp comprising a front member adapted to extend over the front of a necktie, a rear member adapted to claspingly cooperate with the front member to clasp the necktie to the wearer's shirt, and a covering of fibrous material for the front member to conceal the latter and forming a non-slipping tie gripping surface at the rear face of the front member to increase the frictional resistance at the point of clasping action between the front and rear members and to prevent injurious markings on the necktie.
12. A necktie clasp comprising a front member adapted to extend over the front of a necktie, a rear member adapted to claspingly cooperate with the front member to clasp the necktie to the wearer's shirt, a covering for the front member, and relatively soft padding material confined by the covering between the latter and the rear face of the front member.
13. A clasp comprising a rigid front bar and a clasping means coacting therewith, and a covering of flexible material secured to the bar and forming a non-slipping gripping surface at the rear face of the front bar to cooperate with the clasping means and having a cutaway portion to expose a portion of the front surface of the front bar, the exposed portion of the bar being ornamental.
14. A clasp comprising a bar and a clasping means coacting therewith, flexible fibrous material permanently secured on the front and rear faces of said bar and forming a non-slipping gripping surface at the rear face thereof to cooperate with the clasping means, and an ornamental device secured to and exposed from the front face of the bar.
15. A clasp comprising a bar and a clasping means coacting therewith, a fibrous covering for the bar permanently secured thereto, and a strip of metal spirally wound tightly around the covering for ornamental purposes and to assist in holding the covering on the bar.
16. A necktie holder having a front bar of substantially uniform cross-sectional area and provided at one end with a bend, a clasping member and a sheath of soft flexible material open at one end and closed at the other and telescopingly fitted on the front bar and on the bend thereof and forming a non-slipping tie gripping surface at the rear face of the front bar to cooperate with the clasping means in holding a necktie.
